CLASP FOR WRIST-WATCH BRACELETS
AND OTHER LINKAGESLouis E. Valcourt, East Providence, R. I., assignor
to Kestenman Bros. Mfg. Co., Providence, R. I.,
a corporation of Rhode Island

Application December 27, 1946, Serial No. 718,772

10 Claims. (Cl. 24—71)

1

This invention relates to buckles, clasps and similar connectors for watch-bracelets and the like and particularly to improvements in devices of a type comprising means for automatically adjusting the length of the strap, band or bracelet to yieldingly engage the wrist of the wearer.

One object of the invention is to provide an extensible clasp or fastening device of the type indicated which, after it has been slipped over the hand, may have its parts folded into closed relationship and securely latched together while being adapted to yieldingly hold the strap or band contracted on the wrist.

Another object is to provide a clasp or fastening device of the type indicated comprising a plurality of hinged sections adapted to be folded into overlying nested relationship to contract the band or bracelet and embodying a resiliently-operated element slidable in one of the hinged sections for drawing the bracelet snugly about the wrist of the wearer.

Another object is to provide a clasp or fastening device of the type indicated having means for securely latching the foldable sections in closed relationship to guard against their accidental release, with manually-operable means for releasing the latching means only when the extension member has been extended throughout substantially its full length.

Another object is to provide a clasp or fastening device of the type indicated having latching means on one of the foldable sections and means on the slidable extension element for sliding the latching means in one direction when the extension element is extended, whereafter the manually-operable means may be manipulated to release the latching means to permit unfolding of the hinged sections.

Further objects of the invention are set forth in the following specification which describes a preferred form of construction of the device by way of example, as illustrated by the accompanying drawing.

In the drawing:

Fig. 1 is a plan view of the present improved clasping device shown as attached to the ends of a bracelet chain or linkage;

Fig. 2 is a longitudinal sectional view of the clasp taken in a median plane and showing its parts latched together in folded relationship;

Fig. 3 is a similar sectional view showing the hinged members of the clasp in unfolded relationship;

Fig. 4 is a fragmentary sectional view of the foldable members at one end of the clasp illus-

2

trating the manually-operable means for permitting release of the latching means as in position to prevent such release;

Fig. 5 is a similar sectional view at one end of the clasp showing the manually-operable means actuated to permit release of the latching means;

Fig. 6 is a transverse sectional view of the clasp on line 6—6 of Fig. 1;

Fig. 7 is a similar transverse sectional view on line 7—7 of Fig. 1;

Fig. 8 is a detailed view of the hinged connection between two of the foldable members of the clasp;

Fig. 9 is a perspective view of the manually-operable locking means for preventing release of the latching means; and

Fig. 10 is a view of the slidable latching element.

The present clasp or connector is similar in general to that shown and described in my United States Letters Patent No. 2,408,279, but embodies certain improvements including manually-operable locking means to guard against accidental release of the latching means when the extension member is extended. In the device of my prior patent the several foldable elements of the clasp are normally held together by latching means which may be released by drawing out the extension member to the full extent of its sliding action. With this previous form of construction there is an element of danger from accidental unclaspings of the device should the extension member be inadvertently drawn outwardly to the full extent permissible after the bracelet has been clasped on the wrist. To provide against this contingency and render the latching means of the clasp more secure, the present improvement provides a lock in the form of a pivoted detent which must be manually operated to permit the extension member to be drawn out to the full extent for releasing the latching means.

Referring to the drawing, the present improved clasp or connector 2 is shown in Fig. 1 as applied to use attached to the ends of sections 3 and 4 of a bracelet composed of articulated links; while in other cases it may be employed with leather or fabric straps or cords. The device comprises, in general, three cooperating foldable extension members consisting in a base member 5, an intermediate or connecting member 6, and a top member or cover 7. The several members 5, 6 and 7 are hinged together to adapt them to be folded together in overlying relationship as shown in Figs. 1 and 2. A resiliently-operated extension member 8 is slidable in the base member 5 for

permitting limited expansion or contraction in the length of the bracelet after the parts of the clasp have been folded together and latched in closed relationship. The several parts of the device may be constructed as stampings struck up from sheet-metal stock and formed generally of arcuate shape to conform to the contour of the wrist of the wearer.

The base member or section 5 is of shallow trough-shape constituted by a bottom wall or plate 10 having side walls 11 folded upwardly therefrom. At one end of the base member 5 its bottom wall 10 is extended and curled around to provide a cylindrical bearing 12 for a hinge-pin 13, the ends of which project through holes in a pair of opposite ears 14 at the ends of the connecting member 6, see Fig. 8. The intermediate connecting member 6 may take the form of an arcuate strip of sheet-metal which is cut away at its center throughout the greater part of its length to form a pair of bifurcations or legs 15 indicated by dotted lines in Fig. 1. As illustrated in Fig. 3, the ends of the legs 15 of the member 6 are formed with laterally-projecting pintles 16 which project through holes in the sides of the top member 7 to hingedly connect these two parts of the clasp.

The top member or cover 7 is also of arcuate shape in side elevation, being formed with a top wall 17 and depending side walls 18. The lower marginal portions of the side walls 18 are folded inwardly to provide a pair of opposed flanges 20 which serve as ledges for engagement with the latching means carried by the bottom member 5. Adjacent each end of the cover 7 the opposite flanges or ledges 20 are cut away to provide slots 21 and 22 which provide aligned openings for release of the latching lugs, later described, when the latter are brought into cooperative relation therewith. The upper wall 17 of the cover 7 may be embossed with a raised panel 23 as shown most particularly in Figs. 2 and 6. The free end of the cover 7 has its top wall formed into a cylindrical hinge-member 24 for connection with the link at one end of the bracelet as shown in Figs. 1 and 2. Pivottally mounted at the opposite end of the cover 7 is a locking pawl or gate 25 normally maintained in position to close the openings 22 in the ledges 20 for a purpose as later explained.

The locking pawl or detent gate 25, shown in perspective view in Fig. 9, is constructed from relatively thin sheet-metal formed with a cross-strip or saddle 26 folded downwardly at its ends to provide a pair of runner-like legs 27. The legs 27 are pierced with holes 28 for receiving the pintles 16 which project from the legs 15 of the connecting member 6 for hinging it to the sides of the cover 7. The rearward portions of the legs 27 of the locking member 25 are folded upwardly from the bottom to overlap on the inside, thus providing double-thick detent abutments or gate-ports 29 normally engaging through and closing the openings 22 in the opposite ledges or flanges 20 on the cover 7.

Projecting rearwardly from the cross-strip 26 of the member 25 is an integral spring element 30 of bowed form with its end reversely bent to adapt it to bear against the under side of the top wall 17 of the cover 7. The spring 30 thus tends to rock the member 25 to maintain its detent or gate portions 29 engaged through the openings 22 in the ledges 20 on the sides of the cover 7, see Fig. 4. At its forward end the cross-strip 26 of the member 25 has an extension 32

folded upwardly and then rearwardly across the top of the strip 26 to provide a finger-rest 33, the ends of which are folded downwardly at 34 to provide a smooth finish. The finger-rest 33 is normally positioned in an opening 35 where the end of the top wall 17 of the cover 7 is cut away to accommodate it.

The extension member 8 is formed with a top wall 37 and depending side flanges 38 having their edges resting on the bottom of the base member 5 to support the member to slide longitudinally therein. The top wall 37 of the member 8 is bent downwardly at the rear to form an abutment 39 for the end of a helical coiled spring 40, the forward end of which engages against the upturned end wall 41 of the base member 5. A pair of semicircular ears 42 folded inwardly from the side walls 11 of the base member 5 overlap the top of the extension member 8 to assist in holding it down within the base member 5. Normally, the slideable extension member 8 is contracted within the base member 5 as shown in Figs. 1 and 2 under the tension of the spring 40. At its forward end the extension member 8 has its top wall curled around to form a bearing 43 for engagement with the crossbar of one of the links of the bracelet chain 3 as shown in Figs. 1 and 2. The extension member 8 is thus adapted to be slid outwardly from the base member 5 to expand the bracelet; and normally the spring will act to retract the extension member into the base member to draw the bracelet snugly about the wrist of the wearer.

The latching means for the clasp comprises a second slideable member 45 shown in perspective view in Fig. 10 and arranged to overlie the top of the extension member 8. The latching member 45 may be constructed of sheet-metal with an arcuately-shaped top wall 46 and depending curved side flanges 47. The top wall of the latching member 45 is slotted to provide an opening 48 extending substantially its whole length, but interrupted by cross strips 49 at each end. The lower edges of both side flanges 47 are cut away adjacent their ends and the metal bent upwardly and outwardly to form laterally-projecting latching strips or lugs 50 at both ends and each side of the member 45. These latching lugs 50 are arranged to project through longitudinally-extending slots 51 in the sides 11 of the bottom or base member 5 as shown most clearly in Figs. 3 and 6 of the drawing. The slots 51 are of considerably greater length than that of the latching lugs 50 to permit the latching member 45 to slide longitudinally of the base member 5 while holding said member down in the base. It will be noted by reference to Figs. 6 and 10 that the latching lugs 50 are rounded along their outer edges, the purpose being to adapt them to snap across the inturned flanges 20 on the inner sides of the top member or cover 7 to latch the several folded sections of the clasp in closed relationship, see Figs. 5 and 6. Referring to Fig. 7, it will be noted that the detent or gate portions 29 of the legs 27 of the locking member 25 are positioned in the space between the sides 18 of the top or cover member 7 and the side walls 11 of the bottom member 5 in abutting relation therewith. To assist in holding the slideable latching element 45 down within the base member 5 a pair of semi-circular ears 55 are folded over from the side walls 11 of the base member to overlap the top of the latching member as shown in Figs. 1 and 6. Struck up from the top of the extension member 8 is a lug or abutment

56, see Fig. 3, which projects through the longitudinal slot or opening 48 in the member 45 to adapt it to slide therein when the member 8 is drawn outwardly from the end of the base member 5. The abutment 56 is so located on the member 8 as to adapt it to strike the end of the opening 48 in the latching member 45, that is the edge of its forward cross strip 49, to cause the latching member to be slid with the extension member during the latter part of its sliding motion. The purpose of this construction is to adapt the latching member 45 to be slid forwardly into position for its latching lugs 50 to pass through the openings 21 and 22 in the ledges 20 on the side walls 18 of the cover member 7 to unclasp the several foldable members after the locking detent or gate member 25 has been pressed downwardly as shown in Fig. 5. The method of operation of the complete device is as follows:

Assuming that the several foldable elements 5, 6 and 7 have been unlatched and unfolded into alined relationship to extend the bracelet for drawing it over the hand and onto the wrist of the wearer, the clasp may be closed by simply pressing the cover 7 down against the base member 5 with the pivotal or hinge connections providing for such folding together of the parts. As the cover 7 is pressed down onto the base 5 to nest the latter therein, the latching lugs 50 on the member 45 will snap across the edges of the inturned ledges 20 on the cover to engage therewith in the relationship shown in Fig. 6 to hold the several parts in closed or nested relationship. It should be explained that it is not necessary that the latching lugs 50 be disposed opposite the openings 21 and 22 in the ledges 20 since they will snap over the edges of the ledges in whatever relation they assume to the openings. That is to say, normally with the extension member 8 partly or completely contracted to its full extent within the base 5 the latching lugs 50 will not be alined with the openings 21 and 22, but, as before stated, it is not essential that they should be since the lugs will snap over the edges of the ledges 20 in any position they may assume in relation thereto. In such extreme circumstance, however, that the extension member 8 may be completely extended from the bottom or base member 5 the forward lugs 50 on the latching member 45 will be allowed to pass up through the forward openings 22 in the flanges or ledges 20 on the member 7 by rocking the gate member or locking member 25. At the same time the rearward latching lugs 50 will pass through the openings 21 at the opposite end of the cover 7 and immediately thereafter the spring 40 will act to retract the extension member 8 into the base member 5 and slide the member 45 with it, due to frictional contact between these parts to cause latching engagement between the lugs 50 and the flanges or ledges 20 on the cover.

With the parts of the clasp latched together in nested relationship, as shown in Figs. 1 and 2, the device operates to permit a limited extension in the length of the bracelet under the outwardly sliding movement of the extension member 8, such motion being limited by the forward lugs 50 striking against the rearward edges of the folded detent or gate portions 29 of the member 25. When it is desired to unclasp the bracelet to withdraw it from the wrist the extension member 8 is slid outwardly, preferably by pressing the finger on the top of the detent or gate

member 25 to rock the latter into the position shown in Fig. 5 while concurrently continuing the outward sliding movement of the extension member 8. This continued outward movement of the extension member 8 will cause the forward lugs 50 on the latching element 45 to ride in under the legs of the gate member 25 to further lift the ends of its legs and allow the detent lugs to pass through the openings 22 in the ledges 20 on the sides of the cover 7. Concurrently therewith the rearward lugs 50 on the latching element 45 will pass through the openings 21 in the ledges 20 so that the cover 7 will be completely released from the base member 5 and allowed to be swung upwardly and rearwardly to extend the clasp to its maximum length and provide expansion of the bracelet sufficiently to slide it over the hand of the wearer.

It will be observed from the foregoing specification that the present invention provides important improvements in clasps or connectors of the present type, first, by providing for maximum extension of the bracelet to pass it over the hand of the wearer; second, by rendering it easy and convenient to clasp and unclasp the parts; and last and most important, by the provision of positive locking means for preventing accidental release of the clasping means.

While the improved device is herein shown as embodied in a preferred form of construction, it is to be understood that various modifications may be made in the shape and arrangement of its parts without departing from the spirit or scope of the invention. Therefore, without limiting myself in this respect, I claim:

1. A clasp or connector for wrist-watch bracelets comprising a plurality of sections foldable into overlying relationship, latching means on one of said sections, an extension member slideable in one of said sections, resilient means for sliding said section to normally maintain it in contracted relationship, a slideable latching member having means engageable with the first-named latching means to hold the foldable sections in closed relationship, said slideable latching member being movable by and with the extension member to release the latching means, and detent means for normally restricting the movement of the slideable latching member to prevent release of the latching means, said detent means being manually operable to permit the slideable member to be moved to release the latching means.

2. A clasp or connector for wrist-watch bracelets comprising a plurality of articulated sections foldable into overlying relationship, latching means on one of said sections, an extension member slideable in another of said sections for expanding and contracting the length of the bracelet, resilient means for resisting the outward sliding movement of the extension member, a latching member slideable by and with the extension member and having means for engaging the first-named latching means, a resiliently-operated detent for normally engaging the slideable latching member to restrict its sliding motion, said detent means being manually operable to effect release of the slideable latching member to permit it to move sufficiently to release the cooperating latching means.

3. A clasp or connector for wrist-watch bracelets comprising a base section, a cover section, an intermediate member hingedly connecting the base section and cover section to adapt them to be folded into overlying relationship, latching

ledges on the cover section, a latching member slideable in the base section and having means engageable with the ledges on the cover section to hold the sections in closed relationship, an extension member slideable in the base section, a spring for normally maintaining said extension member contracted within the base section, means on said extension member engageable with the latching member to slide the latter to release its latching means from the ledges on the cover section, and detent means for normally limiting the movement of the latching member to prevent the release of its latching means from the ledges on the cover section, said detent means being manually operable to permit the latching member to slide to release its latching means from the ledges on the cover section.

4. A clasp or connector for wrist-watch bracelets or the like comprising a base section, a cover section, means connecting the base section and cover section to adapt them to fold into closed relationship, said cover section having latching ledges at its sides provided with openings therein, a latching member slideable in the base section and having lugs engageable with the ledges on the cover section to latch the sections in closed relationship, said latching member being slideable to adapt its lugs to pass through the openings in the ledges on the cover section to release the latching means, an extension member slideable in the base section and engageable with the latching member to slide the latter to release the lugs from the ledges on the cover section when the extension member is extended to the limit of its sliding motion, a spring for normally maintaining the extension member in contracted relation in the base member, detent means for limiting the sliding movement of the latching member to prevent release of its lugs from the ledges on the cover section, and a spring for normally maintaining said detent means in operative relation to the latching member, said detent means being manually operable to release the latching member to permit it to slide to effect release of its lugs from the ledges on the cover section.

5. A clasp or connector for wrist-watch bracelets or the like comprising a bottom section, a top section, an intermediate member connecting said bottom section with the top section to adapt them to fold into overlying relationship, said top section having latching ledges on its sides provided with openings at the ends thereof, a latching member slideable in the bottom section and provided with means engageable with the ledges on the top section to latch the sections in folded relationship, said engaging means being adapted to pass through the openings in the ledges to unlatch the sections, a pivoted detent member on the top section provided with resilient means for rocking it into position to close the openings through the ledges thereof, an extension member slideable in the bottom section and engageable with the latching member to slide the latter to release its latching means from the ledges on the top section, and a spring for resisting the sliding movement of the extension member, said detent means being manually operable to expose the openings in the ledges on the top section to permit the engaging means on the latching member to pass therethrough.

6. A clasp or connector for wrist-watch bracelets comprising a plurality of articulated sections adapted to fold into overlying relationship, latching ledges on one of said sections having openings at their ends, a latching member slid-

able on another of the sections and having means engageable with the ledges on the first-named section to latch the sections in closed relationship, a manually-operable member on one of the sections having detent means for closing the openings in the ledges to prevent the engaging means on the latching member from passing therethrough, resilient means for maintaining said member with its detent means in closed relationship, a slideable extension member engageable with the latching member to slide the latter to release its latching means from the ledges by passing through the openings therein, and a spring for normally resisting the sliding movement of the extension member to extended relationship.

7. A clasp or connector for wrist-watch bracelets comprising a channel-shaped base section, a cover section of inverted channel-shape having inwardly-extending ledges at its sides, an intermediate member hingedly connecting the base section and cover section to adapt them to be folded into nested relationship, a latching member slideable in the base section and having lugs projecting from its sides through slots in the sides of said base section, said lugs adapted to snap across the ledges on the cover section to latch the sections in nested relationship, an extension member slideable in the base section and provided with means for engaging the latching member to slide the latter into position for its lugs to pass through the openings in the ledges on the cover section, a spring for resisting the outward sliding movement of the extension member, a manually-operable pawl pivoted on the cover section and having detent means engageable with the latching member to limit its sliding movement and prevent release of its lugs from the ledges on the cover section, and resilient means for normally maintaining the pawl in operative position with respect to the latching member, said pawl being manually operable to permit maximum movement of the latching member to release its lugs from the ledges on the cover section.

45 8. A clasp or connector for wrist-watch bracelets and the like comprising a channel-shaped bottom section, an inverted channel-shaped cover section having inturned flanges on its sides forming latching ledges, an intermediate member hingedly connecting the bottom section and cover section to fold into nested relationship, an extension member slideable in the bottom member, a spring for resisting the outward sliding movement of the extension member, a latching member overlying the extension member and having depending sides provided with lugs projecting through slots in the sides of the bottom section, means on the extension member engageable with the latching member to slide the latter to move its lugs into position for disengagement from the latching ledges on the cover section, a pawl pivoted on the cover section and provided with depending detent portions for limiting the sliding movement of the latching member, and a spring for rocking said pawl into operative position with respect to the latching member, said pawl being manually rockable against the action of the spring to move its detent portions out of operative position and permit release of the engaging means on the latching member from the ledges on the cover section.

9. A clasp or connector for wrist-watch bracelets comprising a bottom section, a cover section hingedly connected to the bottom section to adapt it to fold into overlying relation therewith, said

cover section having depending side walls provided with inwardly-projecting latching ledges interrupted by openings at their ends, an extension member slideable in the bottom section, a spring for resisting outward sliding movement of the extension member, a latching member slideable in the bottom section and formed with latching lugs on its sides engageable with the latching ledges on the cover section, means engageable between the extension member and latching member to effect sliding movement of the latter to permit its lugs to pass through the openings in the ledges when the extension member is moved to its maximum extent, and a resiliently-operated pawl pivoted on the cover section and normally maintained in position to restrict the sliding movement of the latching member, said pawl being manually rockable into position to permit maximum movement of the latching member to allow its lugs to pass through the openings in the latching ledges on the cover section to thereby release the latching means.

10. A clasp or connector for wrist-watch bracelets or the like comprising a channel-shaped bottom section, an inverted channel-shaped cover section, means for hingedly connecting the bottom section and cover section to adapt them to fold into nested relationship, said cover section having

its depending sides formed with inwardly-projecting latching ledges interrupted by openings at their ends, a manually-operable pawl pivoted to the cover section and provided with legs formed with gate portions engageable through the openings in the latching ledges on the cover, resilient means for maintaining said pawl with its gate portions engaged through the openings in the ledges of the cover section, an extension member slideable in the bottom section and formed with an upstanding abutment at the top, a latching member overlying the extension member in the bottom section and having a longitudinal slot in its top and depending legs straddling the sides of the extension member, said legs having outwardly projecting latching lugs slideable in elongate slots in the sides of the base section, the abutment on the extension member being slideable in the slot in the top of the latching member and engageable with the ends thereof, and a spring in the bottom section acting on the extension member to contract it within the bottom section while adapting it to be extended therefrom whereby to slide the latching member into position for its lugs to pass through the openings in the ledges on the cover section upon manual operation of the detent pawl.

LOUIS E. VALCOURT.
